UNITED STATES PATENT OFFICE

SEBASTIANO MAGNANO, OF LAWRENCE, MASSACHUSETTS, ASSIGNOR TO MAGNANO CORPORATION, OF LAWRENCE, MASSACHUSETTS, A CORPORATION OF MASSACHUSETTS

TEXTILE MACHINE

Application filed January 26, 1929. Serial No. 335,190.

This invention pertains to apparatus for associating warp yarns or threads with detached loom elements, such for example as stop motion drop pins or wires, and more particularly to apparatus of the general type disclosed in the patent to Dustin No. 1,072,103, September 2, 1913, and in my prior Patents No. 1,512,704, dated October 21, 1904, No. 1,516,675, dated November 25, 1924, No. 1,530,605, dated May 24, 1925, and No. 1,584,236, dated May 11, 1926, and constitutes an improvement upon the apparatus disclosed in said patents.

While the mechanism disclosed in said patents is of operative and practical character I find it desirable to reduce the size of the machine as much as possible, consistent with durability and accuracy of operation, in order that it may be applied to looms of all usual sizes and types without interference with the loom parts, as well as to reduce weight and facilitate transportation and handling. Furthermore, in order to reduce the initial cost, as well as the cost of upkeep and repairs, I have reduced the number of parts employed but without sacrifice of functional utility. Among the major differences between the present apparatus and those of my former patents, may be mentioned the substitution of a single magazine for a multiple magazine, together with appropriate mechanism for delivering the drop wires from the single magazine, so as definitely and accurately to form a plurality of banks of wires upon the warps. This and other features of improvement will be described more specifically hereafter by reference to the accompanying drawings, in which a preferred embodiment of the invention is shown by way of example.

In the drawings

Fig. 1 is a plan view of the machine;

Fig. 2 is an elevation illustrating the left-hand side of the machine, the supporting rails being shown in section;

Fig. 3 is an elevation illustrating the right-hand side of the machine, the supporting rails being shown in section;

Fig. 4 is a front elevation of the machine;

Fig. 5 is a vertical section substantially on the line 5—5 of Fig. 3;

Fig. 6 is a section similar to Fig. 5, but showing the parts in another position;

Fig. 7 is a vertical section, to larger scale, substantially on the line 7—7 of Fig. 1;

Fig. 8 is a fragmentary vertical section substantially on the line 8—8 of Fig. 7;

Fig. 9 is a horizontal section, to large scale, substantially on the line 9—9 of Fig. 7 illustrating the reciprocating selector device for removing drop wires from the magazine;

Fig. 10 is a rear elevation of the device shown in Fig. 9;

Fig. 11 is a fragmentary vertical section on the line 11—11 of Fig. 9;

Fig. 12 is a fragmentary vertical section, to large scale, substantially on the same plane as Fig. 7 and illustrating details of the stop mechanism for stopping the machine upon exhaustion of the drop wires or failure of the drop wires;

Fig. 13 is a view similar to Fig. 12, but showing the parts in another position;

Fig. 14 is a fragmentary section generally similar to Fig. 13, but to smaller scale, omitting certain parts and showing the relation of the stop mechanism to the magazine;

Fig. 15 is a fragmentary section substantially on the line 15—15 of Fig. 14, showing the parts in front elevation but to smaller scale than in Fig. 14;

Fig. 16 is a section on line 16—16 of Fig. 14;

Fig. 17 is a vertical section substantially on the line 17—17 of Fig. 12 showing details of the electrical contact elements of the stop motion device;

Fig. 18 is a view similar to Fig. 14 but showing the parts in another position;

Fig. 19 is a horizontal section substantially on the line 19—19 of Fig. 17;

Fig. 20 is a fragmentary side elevation from the left-hand side of the machine showing some of the parts which are illustrated in Fig. 5 together with additional associated parts;

Fig. 21 is a fragmentary rear elevation showing the support for the forward end of

the magazine as well as other parts illustrated in Fig. 20;

Fig. 22 is a section on line 22—22 of Fig. 21;

Fig. 23 is a fragmentary plan view showing 5 the forward feed roll and the means for wiping it;

Fig. 24 is a horizontal section substantially on the plane of line 24—24 of Fig. 14;

Fig. 25 is a fragmentary vertical section, to 10 larger scale, substantially on the line 25—25 of Fig. 1, omitting certain parts;

Fig. 26 is a fragmentary horizontal section substantially on the line 26—26 of Fig. 25;

Fig. 27 is a fragmentary plan view of the 15 rear end portion of the magazine carriage;

Fig. 28 is a fragmentary vertical section on line 28—28 of Fig. 27;

Fig. 29 is a fragmentary horizontal section 20 substantially on the line 29—29 of Fig. 27;

Fig. 30 is a fragmentary rear elevation, partly in section, on the plane of line 30—30 of Fig. 7, showing the slide block which supports the follower blade of the magazine;

Fig. 31 is an elevation from the left-hand 25 side showing a modified form of cam for moving the magazine carriage;

Fig. 32 is an elevation from the left-hand side of the machine illustrating a crank disk 30 which actuates the follower plate of the magazine;

Fig. 33 is a fragmentary vertical section 35 substantially on the same plane as Fig. 5, but to larger scale, illustrating the looper device and its actuating means;

Fig. 34 is a fragmentary rear elevation showing one of the bridge pieces and its adjustable thread receiver;

Fig. 35 is a fragmentary front elevation, 40 to large scale, showing one of the bridge pieces with its movable strand positioning elements and the means for imparting motion to the latter;

Fig. 36 is a fragmentary vertical section 45 substantially on the same plane as that of Fig. 8, but to larger scale and omitting parts, illustrating in detail the means for actuating the carriage driving pawl;

Fig. 37 is a fragmentary vertical section 50 in a plane slightly to the rear of the plane of Fig. 36, omitting parts and showing details of the mechanism for intermittently lifting the feeler from the plane of the warp;

Fig. 38 is a fragmentary vertical section 55 substantially in the plane of line 38—38 of Fig. 7 omitting parts and showing the means for actuating the rear holdback finger;

Fig. 39 is a fragmentary vertical section 60 substantially in the plane of line 39—39 of Fig. 7 omitting parts and showing the means for actuating the forward holdback finger;

Fig. 40 is a fragmentary vertical section 65 substantially on the line 40—40 of Fig. 3 omitting parts and showing the means for

transmitting motion from the motor to the drive shafts of the machine;

Fig. 41 is a fragmentary vertical section substantially on the plane of line 41—41 of Fig. 2, omitting parts and showing details of the thread selector device;

Figs. 42 and 43 are perspective views illustrating the operation of the strand separating devices;

Figs. 44 and 45 are diagrammatic plan 75 views respectively illustrating successive cycles of operation of the machine during which drop wires are deposited in two banks upon the warps;

Fig. 46 is a view similar to Fig. 44 but showing the wires arranged in four banks on the warps;

Fig. 47 is a diagrammatic plan view corresponding to Fig. 46, showing the drop wires turned to lie substantially parallel to the 85 warps; and

Figs. 48 to 56 inclusive are diagrammatic 90 views illustrating successive steps in the cycle of operation of the thread separating and positioning devices.

Main frame and drive

Referring to the drawings (Figs. 1, 2, 3 and 7) the frame of the machine comprises a front end member or head 1 and a rear end member 2, the latter preferably being of substantially inverted U-shape. The front and rear members 1 and 2 are connected by the aid of side rails 3 and 4 (Figs. 1 and 3) on the right-hand side of the machine and the single rail 5 (Figs. 1 and 2) on the left-hand side of the machine. The front and rear members 1 and 2 are provided at the right-hand side of the machine (Fig. 3) with brackets carrying supporting rollers 6 and 7 105 respectively. At the other side of the machine (Fig. 2) the members 1 and 2 are provided with bearings for a shaft 8 which carries rollers 9 and 10 respectively. Members 1 and 2 are also furnished with brackets 11 and 12 (Fig. 2) respectively projecting at the left-hand side of the machine and these brackets carry additional rolls 13 and 14 disposed in the same plane as the rolls 9 and 10 respectively. The rollers 6 and 7, and 9 and 10 are designed to rest upon rails 14^a and 15^a respectively. These rails may form a part of the loom but ordinarily may be considered as parts of the present machine and are placed upon the loom frame only when needed.

The rolls 9 and 10 are preferably provided with toothed portions or gear elements 16 and 17 and the rails 14^a and 15^a are furnished with racks 18 and 19 respectively with which these gears 16 and 17 mesh. Preferably the shaft 8 is provided with a hand wheel 20 for turning it manually, thus permitting the machine to be adjusted by hand along the rails 14^a and 15^a if desired.

The machine is also adapted to be auto- 120

5 matically moved along the rails 14^a and 15^a step by step in order to position the mechanism for application of drop wires to successive groups of warp thread. For the purpose of moving the mechanism automatically the shaft 8 is extended forwardly beyond the forward frame or head 1 and carries a ratchet wheel 21 (Figs. 2, 8, 36 and 37) at the front side of the member 1. Shaft 8 also carries a 10 sleeve 22 (Fig. 37) free to turn upon the shaft and having arms 23 and 24 projecting at substantially right angles to each other. A driving pawl 25 is pivotally mounted at 15 26 at the lower end of the arm 24 and this pawl is provided with an arm 27 to which the upper end of a link 28 is pivotally connected. The lower end of the link 28 is furnished with a bracket arm 29 which may be adjustable with respect to the link 28 and 20 to which is attached the stem 30 of a detector or feeler member 31 which is adapted to rest upon the sheet of warp threads. The stem 30 is guided in a fixed guide member 32 projecting from the front frame member 1, and 25 at a point below the bracket 29 the stem 30 passes loosely through a lifter member 33 secured to the forward end of a lifter lever 34 pivotally supported at 35 upon a bracket which projects forwardly from the member 1.

30 A spring 39 tends to raise lever 34, the latter being provided with a cam follower roll 36 which engages a controlling cam 37 upon a shaft 38. Shaft 38 is journaled at its rear end in a suitable bearing carried by the front frame member 1 and at its front end in a bearing provided at the lower end of a bracket 40 projecting forwardly and downwardly from the member 1. The shaft 38 is furnished with a sprocket wheel 41 (Figs. 8 and 40) at a point closely adjacent to the frame member 1. This sprocket wheel 41 receives a driving chain 42 which engages a sprocket wheel 43 mounted upon the forward end of a main drive shaft 44 (Figs. 1, 3, 4, 5, 6, 8, 40). This main drive shaft is journaled at its forward end in a bearing boss provided in the front frame member 1 and near its rear end in a bearing provided in a bracket 45 (Fig. 50 3) secured between the connecting rails 3 and 4. The tension of the chain 42 may be adjusted by means of suitable rollers 46 and 47 (Fig. 40) carried by an adjustable bracket 48 secured to the frame member 1.

55 A link 49 (Figs. 4, 8 and 36) is pivotally secured to the arm 23 of the sleeve 22 carried by the forward end of the shaft 8 and at its lower end this link 49 is pivotally secured at the point 50 to a lever 51 pivotally mounted 60 on the pin 35 above described. This lever 51 carries a cam follower roll 52 which engages a cam 53 mounted upon the shaft 38. A spring 54 connected to the arm 23 holds the follower roll 52 in contact with the cam 53.

65 Just forward of the sprocket wheel 43

(Figs. 8 and 40) the shaft 44 carries a second sprocket wheel 55 (Fig. 40) which is engaged by a sprocket chain 56 passing over a sprocket wheel 57 on a shaft 58 journaled in a casing 59 (Figs. 1, 3, 4, 40) secured to or forming part of the frame member 1. This casing 59 encloses a reduction gearing of any usual type adapted to transmit motion from the shaft of an electric motor 60 to the shaft 58. The motor 60 is conveniently mounted 70 upon the top of the frame member 1 by means of a clamping bracket 61. Suitable switches or other controlling devices may be provided for this motor, but such devices are omitted from the present drawings.

In order to keep the chain 56 under proper tension an adjustable tensioning sprocket 62 (Figs. 4 and 40) is provided. This sprocket is carried by a shaft mounted upon a bracket which is adjustable in a slot 62^a (Fig. 8) in 80 the member 1 of the frame.

A gear 63 (Figs. 3 and 4) is mounted upon the forward end of the shaft 44 in front of the sprocket wheel 55. This gear 63 meshes with a gear 64 (Fig. 3) turning upon a stub 90 shaft carried by a bracket 65 (Fig. 3) projecting forwardly from the front member 1 of the frame. A crank disk 66 (Figs. 3 and 4) is attached to the gear 64 and turns with the latter. The crank disk carries a crank 67 (Fig. 4) which is received in a slot 68 in the upper end of a link 69 (Figs. 4 and 8). The lower end of the link 69 is pivotally connected at 70 to one end of a lever arm 71 which is fixedly secured to the forward end of 100 a shaft 72 (Figs. 2, 4, 5, 6, 8, 35). This shaft 72 is journaled near its forward end in a suitable bearing opening in the front frame member 1 and near its rear end in a journal opening provided in a bracket 73 (Fig. 2) 105 which is secured to the side rail 5. The purpose of this shaft 72 will be described more at length hereafter.

Thread manipulating mechanism

A shaft 74 (Figs. 1, 2, 4, 5, 6, 8, 35) is fixedly secured at one end in a bracket 75 (Fig. 2) projecting forwardly from the frame member 1 and at its other end in a bracket 76 (Figs. 1, 2 and 4) attached to the bracket 40 above described. A lever 77 (Fig. 38) is mounted to swing freely upon the shaft 74 at a point just forward of the bracket 75. This lever 77 comprises an arm 78 (Figs. 4 and 38) to which one end of a spring 79 is fixed. The upper end of the spring 79 is secured to an arm 80 carried by a bracket 81 secured to the shaft 74. The lever 77 also comprises an arm 82 to which the upper end of a link 83 (Fig. 38) is pivotally connected. The lower end of the link 83 is pivotally secured at 84 to one end of a lever 85 which is fulcrumed at 86 upon a pin carried by a forwardly projecting bracket arm 87 provided with a base 88 attached to the front 120 125 130

face of the member 1. The lever 85 is provided with a cam follower roll 89 which engages a cam 90 mounted upon the shaft 38 above described. The lever 77 is provided with an opening for the reception of the upper end of a hold back finger 90 which is adjustably secured in position by means of a set screw 91. The lower end of this hold back finger 90 is provided with a hook 92 for engagement with the warp threads in a manner hereinafter more fully described.

The bracket 81, above described, is provided with a sleeve-like portion 93 (Fig. 2) embracing the shaft 74 and to which it is connected by means of a set screw or other suitable means. Forward of this sleeve a second lever 94 (Figs. 2 and 39) is mounted to turn freely on the shaft 74. This lever 94 is provided with an arm 95 connected by means of a spring 96 to an arm 97 also forming a part of the bracket 81. The lever 94 also comprises an arm 98 to which the upper end of a link 99 is pivotally connected. The lower end of this link 99 is pivotally secured to one end of a lever 100 fulcrumed at 101 upon a pin carried by a bracket 102 secured to the lower end of the bracket 40 above described. The lever 100 carries a cam follower roll 103 which engages a cam 104 mounted upon the shaft 38 above described.

The lever 94 is provided with an opening for the reception of the upper end portion of a second hold-back finger 105 which is adjustably secured in position by means of a set screw 106. The lower end of this hold-back finger is bent to provide a hook portion 107 which is adapted to engage and to hold back certain of the warp threads as hereinafter described.

The cams 90 and 104 are spaced apart on the shaft 38 and between them a sleeve 108 (Figs. 2, 3, 7, 41) is mounted upon the shaft 38 and fixedly secured thereto. The sleeve 108 is provided with oppositely extending arms 109 and 110 having transversely extending end portions 111 and 112 respectively, such end portions being substantially parallel to each other. Blade carriers 113 and 114 are adjustably secured to these members 111 and 112 by means of set screws 115. Each blade carrier is provided at one end with a slit for the reception of a thin resilient warp separating blade 116. These blades are secured within their respective slots by means of set screws 117.

The bracket 73 (Fig. 2) which furnishes a bearing for the rear end of shaft 72 above described is mounted upon the left-hand rail member 5. At the opposite side of the machine a bracket 118 (Fig. 3) is secured to the rail member 3 and the lower ends of the brackets 73 and 118 are united by a bridge member 121 (Figs. 2, 3, 5, 6, 7, 34, 35) which is vertically adjustable. At a point just forward of the bracket 45 (Fig. 3) which sup-

ports the rear end of shaft 44, a second bracket 120 is secured to the rail 3 and, at a point opposite, a bracket 119 (Fig. 2) is secured to the rail 5. The lower ends of the brackets 119 and 120 are connected by a bridge member 122 (Figs. 2, 3 and 7) similar to the bridge member 121, and also vertically adjustable. The bridge members 121 and 122 are of substantially like construction. As shown in Figs. 5, 6, 34 and 35, the bridge member 121 is provided with a lower surface 123 whose central portion is substantially horizontal and which is in a plane somewhat below the plane of the sheet of warp threads. The left-hand ends of the bridge members are curved upwardly to form horns 124, adapted to engage the foremost threads of the warp sheet and to guide the threads downwardly into contact with the substantially horizontal lower surface 123.

Each bridge member carries a set of thread manipulating instrumentalities, the instrumentalities on one bridge member duplicating those upon the other. These instrumentalities (Fig. 35) include a thread "positioner" comprising a lever 125 having a substantially straight thread engaging and positioning surface 126. This lever 125 is pivotally supported upon a stud 127 projecting from the corresponding bridge piece. A second lever provided with a hook-like lower end 128 (constituting a thread engaging clamp for clamping the thread against the positioning surface 126) is also mounted upon the stud 127.

A lever having a curved lower end 129 and which is hereafter termed a "pusher" is pivotally supported upon a stub shaft 129^a projecting from the bridge member. The levers 129 and 125 are connected by a link 130 so that movement of the lever 125 is imparted to lever 129. The point of connection of the link 130 to the lever 129 is nearer the fulcrum of the latter than is the point of connection of link 130 to fulcrum of the lever 125. It follows that the lever 129 will move more rapidly than the lever 125.

Links 131 and 132 connect the levers 125 and 128, respectively, to one end of a bell crank lever 133 pivotally supported at 134 upon a stud projecting from the corresponding bridge member. This bell crank lever has an upwardly extending arm 135 which is slotted or forked at 136 near its upper end for the reception of an adjustable shouldered stud 137. This stud 137 is received between a pair of arms 138 and 139, the arm 138 being clamped or otherwise fixedly secured to the shaft 72 above described. The arm 139 is pivotally secured to the arm 138 at the point 140 and a spring 141 connected to a tail member 139^a projecting from the arm 139 tends to swing the arm 139 toward the arm 138 thus normally clamping the headed stud 137 between these arms. This arrangement pro-

vides for a yielding movement of the thread actuating instrumentalities in one direction while positively moving them in the opposite direction. It is to be understood that a lever 133 with corresponding actuating means is provided for each set of thread manipulating instrumentalities. The corresponding arms 138 are clamped to the shaft 72 at points adjacent to the front plate 1 of the machine and to the bracket 73 respectively.

Just to the rear of the front plate 1 and between the latter and the front bridge member 121, a bracket 142 (Fig. 33) is secured to the right-hand rail 3. The lower end of this bracket 142 provides a pivotal support for a lever 143 carrying a cam follower roll 144 engaging a cam 145 mounted upon the drive shaft 44, above described. A spring 146 attached to the lever 143 and to a part fixed to the frame tends to hold the follower roll 144 in contact with the cam 145. The lever 143 is provided with an offset arm 147 having an opening for the reception of the upper end of a looper member 148 which is adjustably clamped in the arm 147. This looper member is provided near its lower end with a thread engaging hook portion 149.

Preferably each bridge piece is furnished with an adjustable member 150 (Fig. 34) having a substantially vertical end surface 151 constituting a thread receiver. The member 150 is conveniently attached to the bridge piece by the same stud 134 which carries the lever 133 (Fig. 35) and is adapted to swing vertically about such stud as a pivot. The member 150 is provided with a curved slot 152 which receives a set screw 153 by means of which the member 150 may be retained in adjusted position. By swinging the member 150 about the stud 134, the lower extremity 155 of the member 150 may be adjusted with respect to the plane of the surface 123. Preferably the lower edge of the member 150 is curved as indicated at 156 to assist in guiding the thread to the lower extremity 155 of the member 150. While it is preferred to employ an adjustable member 150 as just described, it is possible to dispense with such adjustable member and to provide the vertical thread retaining surface 151 directly upon the bridge piece itself, but in order to accommodate the device to warps of different character it is desirable to employ the adjustable member 150. It is to be understood that each bridge piece is furnished with one of the thread positioners 150.

Magazine carriage

The magazine and associated mechanism for applying and distributing the drop wires is supported by a carriage comprising the spaced parallel side rails 157 and 158, (Figs. 1, 27 and 29) connected at their front and rear extremities by means of headers 159 and

160 (Fig. 1). This carriage is supported to reciprocate upon the side rails 4 and 5 by means of flanged rollers 161 and 162 respectively (Fig. 1). To assist in guiding the carriage in its reciprocating movement, rollers 163 and 164, turning upon vertical axes, are mounted upon the frame member 2, such rollers engaging the outer vertical surfaces of the side members 157 and 158 of the carriage.

The means for reciprocating the carriage comprises a beveled gear 165 (Fig. 3) secured to the rear end of the drive shaft 44 and meshing with a beveled gear 166 mounted upon a transverse shaft 167. This shaft 167 is journaled at its right-hand end in a bracket 168 secured to the right-hand frame member 3. To the left of the gear 166, shaft 167 is supported by a sleeve 169, Fig. 7, projecting inwardly from the bracket 45. The opposite end of this sleeve is held in a clamp 170 forming a portion of a bracket 171 (Fig. 2) secured to the longitudinal frame member 5 at the left-hand side of the machine.

The shaft 167 projects beyond the left-hand frame member 5 and a cam 172 (Figs. 2, 3, and 7) is secured to this projecting end of the shaft. This cam is furnished with a cam groove 173 in its inner face, which receives a cam follower roll 174 carried by a lever 177 pivotally supported at 175 upon a downwardly directed extension 176 of the bracket 171. The upper end of the lever 177 is pivotally connected at 178 to a connecting rod 179 (Fig. 2) preferably adjustable in length and whose forward end is pivotally connected at 180 to the front end member 159 of the carriage. Preferably the pivotal connection at the point 180 is of such character as to permit the connecting rod 179 to be disconnected from the carriage if desired to facilitate adjustment of or removal of parts mounted upon the carriage.

As shown in Figs. 2 and 7 the cam 172 has a groove 173 provided with two pairs of oppositely disposed dwell portions. As thus arranged the carriage is alternately moved from front to back, the front and rear positions always being the same. Thus as shown in Fig. 44 the drop wire *a* is deposited upon the first warp thread *Y* when the carriage occupies its forward position. The next drop wire *b* is deposited upon the next warp thread *Y*¹ when the carriage occupies its rearmost position. The next drop wire *a'* is deposited upon the next warp thread *Y*² when the carriage occupies its forward position, (the wires *a* and *a'* being disposed in the same plane). At the next return of the carriage to its rearmost position the next drop wire *b'* is placed upon the warp *Y*³, (the wires *b* and *b'* lying in the same plane) thus forming two banks of wires upon the warps,—the wires, after being placed on the warps, turning so as to lie substantially parallel to the warp strands as shown in Fig. 45.

An alternate arrangement of the cam is illustrated in Fig. 31 and the resulting arrangement of the drop wires is shown in Figs. 46 and 47. Cam 172^a (Fig. 31) is provided with a cam groove 173^a having four dwell portions disposed at different distances from the axis of the cam, successive dwells being at successively increasing distances from the axis. When such a cam is employed drop wires *c* and *c'* lying in the same bank upon the warp threads occur at each fourth warp rather than at alternate warps. Likewise wires *d* and *d'* occur at every fourth warp, the wires *e* and *e'* at every fourth warp, and the wires *f* and *f'* at every fourth warp. With this arrangement the drop wires are disposed in four banks instead of in two as with the cam shown in Fig. 7.

Obviously by providing the cam with a greater or lesser number of dwells the number of banks of wires may be varied, and by arranging successive dwells in a different order with respect to their distance from the axis, successive wires may be placed in adjacent banks or in banks spaced from each other by intervening banks, as desired.

Wire delivering mechanism

The front end member of the magazine carriage is extended upwardly to provide a post 159^a. This post is furnished with a vertical guide groove 181 (Fig. 26) extending from a point near its top to a point near its bottom and this guide groove receives a vertically sliding picker block 182 (Figs. 9, 11, 26). This picker block has a vertical bore for the reception of a guide rod 183 (Figs. 9, 11, 25, 26) fixedly secured at its upper and lower ends in the post 159^a.

A plate 184 (Fig. 25) is attached to the rear face of the post 159^a by means of screws 185. This plate is furnished with a vertical guide groove 186 which registers with the guide groove 181 in the post proper. The upper part of the guide groove 186 receives a vertically adjustable bar 187 having a slot 188 for the reception of a set screw 189 having threaded engagement with a transverse web portion 184^a of the plate 184. The lower end of the bar 187 is furnished with a rearwardly extending substantially horizontal stop ledge 190 adapted to prevent upward movement of drop wires with the picker block as the latter moves upwardly in its guide groove.

The lower portion of the plate 184 is furnished with a pair of spaced, parallel, vertical flanges 191 and 192 whose inner faces are in alignment with the opposite sides of the groove 186. These flanges 191 and 192 define a chamber 194 constituting the edge or end of the drop wire magazine.

The rear face of the picker block 182 is provided with an accurately finished surface 195 (Figs. 10 and 11) for engagement with

the endmost drop wire in the magazine. Preferably this surface 195 is divided by grooves in order to reduce the contact surface between the picker block and the drop wire, thus facilitating accuracy of contact. At a suitable point in the upper portion of the block 182 a transverse groove 196 (Figs. 10 and 25) is formed. Above this groove the contact surface of the block which engages the drop wire is disposed in a plane slightly to the rear of the engaging surface of the lower part of the block. This upper engaging surface is also divided by vertical grooves into portions 197 and 198 (Figs. 10 and 25). Preferably the central portions of these surfaces merge at their lower ends as indicated at 199. The lower ends of the members 197 and 199 (at the edge of groove 196) constitute a picker element for engagement with the upper end of the endmost drop wire in the magazine. As indicated in Fig. 11, the parts 197 and 199 project rearwardly beyond the plane of the surface 195 to a distance which is not greater than the thickness of a drop wire and which is preferably slightly less than such thickness so as to insure engagement of the lower ends of the parts 197 and 198 with but a single drop wire at a time.

In Figs. 11 and 10 the endmost drop wire D¹ (indicated in broken lines in Fig. 10) is shown in engagement with the lower edge of the part 199 and in Fig. 11 this endmost drop wire is shown as having been slightly depressed below the level of the remaining drop wires in the magazine.

The picker block 182 is reciprocated along the post 183 by suitable mechanism, such mechanism comprising a bracket 200 (Fig. 7) projecting forwardly from the block 182 and pivotally connected to the upper end of an eccentric rod comprising an upper section 201 and a lower section 202. Parts 201 and 202 are adjustably connected by means of a slot 203 in the part 202 and a pin 204 carried by the part 201. By adjustably fixing the pin 204 to the part 203 the effective length of the connecting rod may be varied and thus the limit of the path of movement of the block 182 may be changed to accommodate drop wires of different lengths.

The lower section 202 of the eccentric rod is connected to an electric strap 205 (Figs. 6, 7 and 24) embracing an eccentric 206 (Figs. 7 and 24) mounted upon a transverse shaft 207. This shaft 207 is journalled in bearings 208 and 209 carried by brackets 210, (Fig. 3) 211 (Fig. 2) respectively, projecting downwardly from the front member 159 of the carrier.

The right-hand end (Fig. 24) of the shaft 207 projects beyond the bearing 208 and has affixed thereto a bevelled pinion 212 which meshes with a beveled gear 213 splined to the shaft 44, this splined connection between the shaft and gear being indicated at 214

(Figs. 1, 3, 24). The gear 213 is thus caused to turn with the shaft 44 but is free to move edgewise along the shaft.

The gear 213 is provided with an elongate hub which turns in a bearing 216 (Fig. 3) supported by a bracket 217 secured to the side member 3 of the carriage. An anti-friction thrust bearing 218 is preferably interposed between the bearing 216 and the gear 213. As thus arranged the gear 213 is constrained to partake of the reciprocating motion of the carriage, while at the same time it is also in driving engagement with the shaft 44.

15 A large feed roller 219 (Figs. 5, 7, 12, 14, 24) is fixedly secured upon the shaft 207 between the bearings 208 and the eccentric 206, and this feed roller cooperates with a small roller 233 hereafter described to feed the 20 drop wires one by one downwardly onto the warp threads.

25 Downwardly projecting parallel brackets 220 (Fig. 3) and 220^a (Fig. 2) are secured to the side members 157 and 158 respectively of the carriage. A clamping block 222 (Figs. 20, 21, 22) is secured between the brackets 220 and 220^a by means of a bolt 221. This clamping block 222, the purpose of which will be more fully described hereafter, is provided with outwardly and downwardly directed legs 223 and 224 which support a transverse pin 225 to which one end of a tension spring 240 hereafter to be described is attached. A pin 227 projects from the 35 right-hand end of the bolt 221 and constitutes suitable point of attachment for another tension spring 245, hereafter described.

30 The brackets 220 and 220^a are continued downwardly below the bolt 221 and support a transverse shaft 228 (Fig. 20) upon which is mounted a sleeve 229. This sleeve is provided with upwardly extending parallel arms, 230 and 231 (Fig. 13) provided at their upper ends with bearings for a shaft 232 upon which the small feed roller 233 is secured. The roller 233 cooperates with the large feed roller 219 above described to feed the drop wires downwardly from the magazine. The roller 233 is mounted between the arms 230 45 and 231 and the shaft 232 projects beyond the arms 231 and is provided with a pinion 234 (Figs. 12 and 15).

50 The sleeve 229 is provided with downwardly directed arms 235 to which a wire guiding block 236 is secured. This block 236 is elongate in a vertical direction and is provided with a smooth front face 237 for engagement with the drop wires as they are moved downwardly by the feed rolls. Preferably this face 237 is provided with a forwardly extending rib 238 substantially midway its width, such rib being adapted to enter between the legs of the drop wire and thus accurately to guide the latter as it moves 55 downwardly toward the warp thread which

is in position for receiving it. Preferably the upper portion of the forward face 237 of the block 236 is inclined rearwardly as indicated at 239 and the upper end of this face terminates closely adjacent to the periphery of the roller 233 and at a point to the rear of the vertical plane of the bite of the rolls.

70 One end of the tension spring 240 is connected to the downwardly extending member 235, its opposite end being secured to the bar 225 above described. The tendency of this spring is to swing the member 235 and the sleeve 229 in such a direction as to cause the roller 233 to press forcibly against the periphery of the roller 219.

Wire exhaust stop mechanism

75 The bracket 220^a is extended downwardly below the shaft 228 as indicated at 242 (Figs. 14 and 15) and at its lower end is provided with a stub shaft 243 forming a pivot for a lever 244 (Figs. 2, 13, 15). The spring 245 is connected at one end to the upper end of the lever 244 and its other end to the pin 227 above described. The lower end of the lever 244 is provided with a pin 246 which is normally held in engagement with the back side of the block 236 by the action of the 80 spring 245.

85 A bracket 247 (Figs. 12, 13, 14, 20) is fixedly attached to the lever 244 at a point spaced from the upper end of the latter and this bracket 247 extends rearwardly and is provided with an insulated contact member 248 (Figs. 17 and 20) forming one terminal of the electrical circuit of the motor 60.

90 The lever 244 also carries a stub shaft 249 forming a pivotal support for a lever 250. This lever has a rearwardly extending arm carrying an insulated contact member 251 adapted to engage the contact 248 to complete the circuit to the motor. The lever 250 also has a forwardly extending arm 252 (Fig. 20) which is adapted in certain positions of the parts to lie in the path of a rotating cam or finger 253 (Figs. 12 and 24) projecting from the hub of a crank disk 254 mounted on a shaft 207. When the machine is in operation and drop wires are passing in orderly fashion 95 downwardly from the magazine and between the rollers 219 and 233, the roller 233 is forced rearwardly in opposition to the springs 240 and 241. The lower end of the block 236 thus moves forwardly permitting the pin 246 to move forwardly in response to the tension of the spring 245. As the upper arm of the lever 244 is much longer than its lower arm, a very slight forward movement 100 of the pin 246 results in a substantial movement of the upper end of the lever 244 sufficient to withdraw the arm 252 of the lever 250 from the path of the cam finger 253, as shown in Fig. 12. Thus as the shaft 105 110

115 rotates, the cam finger 253 passes the 120 125 130

arm 252 without engaging the latter thus permitting the contact 251 to remain in engagement with the contact 248 so that the motor circuit is unbroken and the motor continues to operate. If, however, the picker device fails to deliver a drop wire to the bite of the rolls 219 and 233, the roll 233 is permitted to approach the roll 219, thus allowing the lever arm 235 and the block 236 to swing rearwardly and causing the pin 246 to move rearwardly. The upper end of lever 244 is thus moved forwardly a considerable distance and swings the arm 252 into the path of the cam finger 253, as shown in Fig. 13, and when the finger 253 engages the arm 252 the contact member 251 is raised from contact 248, thus breaking the motor circuit and stopping the machine.

A bracket 159^b (Fig. 26) extends forwardly from the lower part of the head 159 and supports an arm 255 carrying a box 256 containing a pad 257 which engages the peripheral surface of the large feed roller 219. This pad constantly wipes the face of the roller while the machine is in operation, keeping it clean and free from oil, and thus preventing the transfer of oil to the drop wires.

Magazine and wire compacting means

30 The reciprocating magazine carriage comprises a pair of screw-threaded rotary shafts 258 and 259 (Figs. 1 and 27) which extend in parallel relation longitudinally of the carriage, and which are journalled at their opposite ends in the end members 159 and 160 of the carriage. At the rear end of the carriage the screw-threaded shafts 258 and 259 extend out through the end member 160, and at their outer end are provided with gears 260 and 261 respectively. These two gears mesh with a centrally disposed gear 262 turning freely upon a stub shaft projecting rearwardly from the end member 160 of the carriage. As thus arranged the screw-threaded shafts 258 and 259 are constrained to turn in the same direction and at substantially the same rate and these shafts are threaded to the same pitch and in the same direction.

50 A beveled pinion 263 is secured to the gear 261 to turn with the latter, and this pinion meshes with a pinion 264 mounted upon a transverse shaft 265 journaled in bearings 266 and 267 supported by brackets projecting upwardly from a block 268 attached to the rear face of the end member 160 of the carriage.

The shaft 265 is provided with a friction clutch disk 269 (Fig. 27) secured thereto at a point adjacent to the bearing 267, and this friction disk cooperates with a friction disk 270 loose upon the shaft. The disk 270 is secured to a ratchet wheel 271 which is normally engaged by a pawl 272 having a suitable spring for holding it in engagement with the ratchet wheel, such pawl being pivotally mounted upon an arm 274 swinging

freely upon the outer end of the shaft 265. The outer end of the arm 274 is connected by a pin 275 to a connecting rod 276 which extends forwardly and is connected to a crank pin upon the disk 254, above described. Thus at each rotation of the disk 254 the arm 274 is rocked, causing the pawl 272 to advance the ratchet wheel 271 and the clutch disk 270.

70 A coiled spring 277 encircles the outer end of the shaft 265 and is held under adjustable compression by means of a nut 278. By properly adjusting the tension of this spring the frictional engagement of the clutch disk 269 with disk 270 may be so determined that under normal conditions the advancing movement of the ratchet wheel 271 will cause a corresponding movement of the shaft 265 and thus, through the gear connections, above described, will turn the screw shafts 258 and 259 simultaneously. However, if the shafts 258 and 259 should meet a substantial resistance, the disks 269 and 270 may slip relatively to one another, thus preventing breakage of parts.

75 Preferably I mount a bracket 279 (Figs. 1, 90 27) upon the rear part of the carriage, such bracket being provided with a stub shaft 280 supporting a large gear 281 which meshes with a relatively small gear 282 secured to the gear 262 above described. The gear 281 is conveniently provided with a handle 283 by means of which it may be rotated by hand. Thus by turning the gear 281, the gear 262 may be rotated, thereby turning the shafts 258 and 259 manually. During such actuation of the gear 262, the clutch disks 269 and 270 slip relatively to one another thus permitting this manual movement without reference to the operation of the crank disk 264.

100 The rear member 160 of the carriage is preferably provided with a forwardly extending flange 160^a (Figs. 27 and 28) at its top, and this flange is provided with a smooth bored central opening for the reception of a screw-threaded rod 284. This rod is preferably forked at its lower end, as indicated at 105 285. A coiled spring 286 encircles this rod, bearing at its lower end against the enlargement constituting the top of the forked portion of the rod, and at its upper end against the under surface of the flange 160^a. The upper part of this rod 284 is screw threaded and engages a nut 287 bearing upon the upper surface of the flange 160^a. By turning the nut 287, the rod 284 may be moved vertically in opposition to the tension of the spring 286.

110 A bar 288 (Figs. 1, 27, 28, 29, 30) extends longitudinally of the carriage between the screw-threaded rods 258 and 259. This bar 115 288 is designed to support the series of drop wires, and in a broad sense this bar may be considered as constituting the magazine proper for holding a supply of wires. This bar is preferably narrow, horizontally, so as 120 125 128

to permit the ordinary hair pin drop wire to be straddled over it, but is preferably quite deep vertically to prevent the drop wires resting thereon from swinging sidewise. Preferably the bar 288 is provided with an elongated opening 289 to decrease its weight and is furnished with an accurately straight and preferably somewhat rounded upper edge 290 (Fig. 30) upon which the drop wires rest.

10 The rear end of the bar 288 is furnished with a rearwardly extending toe 291, (Fig. 28) which enters the slot in the forked lower end of the rod 284 and is pivotally secured to said rod by means of a transverse pin 292.

15 The bar 288 is provided near its forward end (Figs. 20 and 22) with a downwardly projecting portion 295, which is received in a vertical slot in the bracket 222, above described. Preferably the portion 295 is furnished with a vertical slot 296 to receive a clamping screw 297 having threaded engagement with an opening in one side wall of the bracket 222. The arrangement just described permits the bar 288 to be adjusted vertically and the rear and front ends of the bar may be adjusted independently of one another so that if desired the upper edge of the bar may be inclined with respect to the horizontal.

30 The extreme forward edge 298 (Fig. 14) of the bar is disposed closely adjacent to the rear face of the picker block 182. The distance between the end face 298 of the bar 288 and the rear faces of the ribs 195 (Fig. 10) 35 upon the picker block in substantially equal to the thickness of one of the drop wires or very slightly greater, so that the endmost drop wire may escape from the bar 288 and be pushed downwardly between the end of the bar 288 and the face of the picker block.

40 this set 28, and the base of the poker block.
Preferably a bracket 299 (Fig. 28) is
secured to the forward edge of the flange 160^a
of the rear member of the carriage, and this
bracket 299 is provided with spaced parallel
45 downwardly extending legs 300 and 301 (Fig.
29) disposed at opposite sides of the bar 288,
thus preventing it from tilting sidewise.

Below each of the rods 258 and 259 is arranged a guide rod 302 and 303 respectively. These guide rods are preferably smooth, parallel, and secured at their opposite ends to the forward and rear members 159 and 160 respectively of the carriage. The rods 302 and 303 form guides for a sliding block 304 (Figs. 1, 7, 30) having screw-threaded openings for the reception of the shafts 258 and 259 respectively. Thus when the shafts 258 and 259 are rotated this block 304 is caused to move longitudinally of the carriage. Block 304 is furnished with a slot 305^a for the bar 288.

Spaced brackets 305 and 306 (Fig. 30) project upwardly from the block 304 and support a transverse shaft 307 (Fig. 7) forming a pivotal support for an arm 308. This arm

has a rearwardly extending tail 309 to which one end of a coil spring 310 is secured, the other end of the spring being attached to the block 304.

The arm 308 has a downwardly directed portion provided with an internally screw-threaded bore receiving the upper end of a threaded rod 311 whose lower end has screw-threaded engagement with a bracket member 312 (Fig. 7) provided with forwardly projecting lugs or ears 313. These lugs or ears support a pivot pin upon which is mounted a follower plate 314, which normally bears against the rear-most drop wire of the mass of drop wires D resting upon the upper edge of the magazine bar 288. The spring 310 tends to swing the arm 311 forwardly and thus to press the follower plate 314 forcibly against the drop wires in the magazine, thus compacting the latter but permitting a certain amount of yield sufficient to take care of any slight inaccuracies in the feed movement imparted to the block 304 by the rotation of the screw-threaded rods 258 and 259 as actuated by the pawl and ratchet mechanism above referred to.

Opération

The operation of the mechanism is substantially as follows, it being assumed that the rails 14 and 15 which support the mechanism are disposed transversely of the threads of the warp sheet; that the magazine bar 288 has been supplied with a quantity of drop wires D which are pressed forwardly against the rear face of picker block 182 by the action of the spring 310; that a drop wire has been fed downwardly between the rolls 219 and 233 so as to hold the latter roll in its rearward position, thus permitting the contact points 251 and 248 to engage thereby completing the driving circuit at this point; that the feeler member 31 is supported by threads of the warp sheet so as to hold the feeding pawl 25 out of operative position; and that the separating blades 116 are disposed to turn in the vertical plane of the crossing of the leased warps.

For best results I prefer as disclosed in my Patent No. 1,516,675, dated November 25, 1924, to lease the warps by means of a pair of large lease rods 320 and 321 (Figs. 42 and 43) and an intermediate pair of small lease rods 322 and 323. The large lease rods keep the upper and lower warp sheets W' and W² spaced apart a sufficient distance for proper operation of the hold-back members 92 and 107, while the small lease rods provide a sharp and definite crossing point of the warps, accurately disposed in the vertical plane of rotation of the separator fingers 116, which for convenience in describing the operation, are hereinafter designated as 116^a and 116^b. 115 120 125

It is assumed that the picker block 182 is 130

at its uppermost position and that the warp a of the upper sheet to the left, as viewed in Fig. 43, has been separated from the main body of the warps, has been provided with a 5 drop wire D^1 , and is now engaging the vertical retained surface 151. The hold-back member 107 is now engaging the foremost warp a^1 . Fig. 43, of the series W^1 , while the separator finger 116^a is just coming into engagement with the foremost warp b of the series W^2 , and the hold-back finger 192 has just risen sufficiently to release this warp b from the other warps of the series W^2 . This position of the parts is indicated in Fig. 43 and 10 diagrammatically in Fig. 48. In the latter figure the looper 149 is at the extreme left-hand end of its path and at this time lies above the lower edge 123 of the corresponding bridge member 121. The clamp 128 also 15 lies at the extreme left-hand end of its path of movement and its hooked point is nearly at the level of the edge 123. The pusher 129 and the positioner 125 are near the right-hand end of their paths.

20 25 As the machine continues to operate the separator finger 116^a swings downwardly to a substantially vertical position, as shown in Fig. 49, the other thread manipulating devices remaining motionless until the separator 30 35 40 45 50 55 60 65 70 75 80 85 90 95 100 105 110 115 120 125 130 has substantially reached this vertical position. The positioner 125 and pusher 129 now begin to move slowly toward the left, while the clamp 128 begins to move slowly toward the right, as seen in Fig. 50.

35 40 45 50 55 60 65 70 75 80 85 90 95 100 105 110 115 120 125 130 This slow movement continues while the separator finger 116^a is swinging upwardly to the position indicated in Fig. 50, but in the meantime the looper 149 begins to move rapidly to the right, its point now projecting below the surface 123 so that when the separator finger 116^a has reached a point in its upward movement such that the thread b escapes from its lower end, the thread is caught by the looper 149, as shown in Fig. 50. The positioner 125 is still moving slowly to the left while the clamp 128 is moving more rapidly to the right until the parts occupy the position indicated in Fig. 51, where the run of yarn engages the forwardly moving face of the looper 149, and the rear face of the pusher 129, and is disposed in the path of the forwardly moving clamp hook 128.

The looper 149 continues to move rapidly to the right while the pusher 129 moves rapidly to the left and the clamp 128 and the surface 126 of positioner 125 approach each other (Fig. 52). A bight of the yarn b now extends around the forward face of the looper, against the face 126 of the positioner 125, over the advancing face of the pusher 129, and beneath the edge 123, this bight being within the hook of the clamp 128. The parts thus continue to move, the looper 149 eventually reaching the position shown in Fig. 53, while the pusher 129 approaches the left-hand end of its

path of its movement and rises sufficiently to release the bight of yarn b . The bight of yarn now extends from the looper around the rear face 126 of the positioner 125 and between the latter and the clamping member 128. At this time the vertical rear surface 126 of the positioner 125 lies substantially in the vertical plane of the rib 238 of the block 236 which guides the drop wires in their downward movement. During the above described movements of the thread actuating elements the picker block has descended from its uppermost position to its lowermost position, and has delivered a drop wire into the bite of the rolls 219 and 233 and these rolls have fed the wire downwardly until at the moment when the thread is clamped between the members 128 and 126, as shown in Fig. 54, the wire is dropped from the rolls and thus rests upon the thread which is accurately positioned at this time by the vertical surface 126 of the positioner 125 against which it is held by the clamp 128.

While the drop wire is thus being placed on the thread, the looper 149 rapidly returns to its original position as shown in Fig. 54, thus releasing the thread b .

The hold-back finger 107, which during this entire interval has been holding back the foremost thread a^1 (Fig. 43) of the warp sheet W^1 now begins to rise rapidly while the hold-back finger 192, which has been in its upper position, begins rapidly to descend until it engages the foremost warp thread b^1 of the series W^2 . By this time the other separator blade 116^b has moved downwardly substantially to the position occupied by the finger 116^a as indicated in Fig. 48 or as shown in Fig. 55 ready to separate the foremost thread a' of the sheet W^1 which has just been released by elevation of the finger 107. As the finger 116^b continues to move downwardly for the purpose of separating the thread a' from the upper sheet, the clamp 128 begins to move rapidly to the left, the pusher 129 swings very rapidly to the right, and the positioner 125 also moves more slowly to the right. The separation of the clamping member 128 from the positioner 125 releases the thread b and the pusher 129 sweeps this thread forwardly until, by the rise of the positioner 125 toward the extreme right-hand end of the path movement, the thread escapes from below the end of the positioner 125 and is eventually moved by the pusher 129 to a point such that it is able to snap up into engagement with the retainer surface 151, this sequence of movement being indicated in Figs. 55 and 56. It may be noted that the position of the parts in Fig. 56 is substantially like that of Fig. 48, and from this point the sequence of operations above described is repeated, it being noted that a thread is alternatively picked from the upper and lower sheet of warp threads, moves forwardly, is

5 accurately positioned, supplied with a drop wire, and then moves forwardly again until it is held by the retainer 151. It is to be understood that the thread actuating elements carried by each bridge piece 121 and 122 are moved in accurate time with each other and in a corresponding manner, both sets of mechanism being driven by shaft 72.

10 During the above sequence of operations the cam 152 moves the carriage so as to deliver successive drop wires in different planes. Thus as shown in Fig. 44 the first drop wire *a* may be delivered upon the warp *Y* at the position indicated. During the interval between the delivery of the wire *a* and the wire *b*, the carriage has moved so that the wire *b* is deposited upon the warp *Y'* in a plane spaced from the plane of the wire *a*.

15 The cam 172 now moves the carriage backwardly so that the third drop wire *a'* which is deposited upon the warp *Y²* lies in the same plane or bank as the wire *a*, and the fourth drop wire *b²* is placed in the same plane or bank as the wire *b*.

20 25 It may be noted that the plane of the drop wire as delivered to the warp thread is perpendicular to the direction of the thread so that it is not necessary to spread the legs of the drop wire or provide guiding means or 30 other devices for enabling the legs of the drop wire to straddle the thread. However, after the drop wires have been placed upon the thread they may readily swing to the position indicated in Fig. 47 so as to form compact banks in the usual manner.

35 While as here shown the carriage is actuated by the cam 172 so as to occupy but two delivery positions alternating one with the other, it is within the range of the invention 40 to construct the cam 172 in such a way as to give this carriage a greater number of delivery positions. For example, the cam may provide three, four, five, or possibly more dwell positions for the carriage so related as 45 to deliver successive drop wires in different planes. It is not necessary that successive wires be delivered in consecutive planes since it is possible to construct the carriage cam so as to cause successive drop wires to be placed 50 in almost any desired order.

55 After the machine has placed drop wires upon a certain number of warp threads the separation of threads from the main body of the warp permits the feeler, detector, or hammer 31 to drop. This allows the pawl 25 to engage a tooth of the ratchet 21 and as the cam 53 rotates, it depresses the lever 23 thus actuating the pawl 25 to rotate the ratchet wheel 21 and thus turn the shaft 8 with its 60 gears 16 and 17, his movement of the gears 16 and 17 causing the entire machine to advance along the rails 18 and 19 so that the thread manipulating devices are placed in position to engage a fresh group of warp threads. Upon the next upward movement

65 of the lever 34 by the action of the spring 39 as permitted by the rotation of cam 37, the feeler or hammer 31, is lifted above the plane of the warps and as the cam 37 rotates, the feeler again drops and rests upon a fresh 70 group of warp threads, which hold the feeler 31 in elevated position, thus keeping the pawl 25 out of engagement with the ratchet 21 until this group of warp threads is also exhausted 75 when the advancing movement of the machine is repeated the same way.

80 As the machine continues to operate, the rotation of the crank disk 254 actuates the rod 276 and the pawl 272, thus advancing the ratchet wheel 271 and turning the shaft 265. 85 This in turn rotates the screw shaft 258 and 259, moving the block 304 forwardly along the guide rods 302 and 303 and thus keeping the follower plate 314 pressed closely against the rearmost drop wire in the magazine. 90 Thus as successive drop wires are removed from the forward end of the magazine and delivered endwise by the reciprocating picker 199 through the space 298 at the extreme forward end of the magazine bar 288, the mass 95 of drop wires in the magazine is bodily advanced so that at each downward reciprocation of the picker 199 a drop wire is disposed with its upper end in the path of movement of the picker, such drop wire being resiliently pressed against the rear face of the picker block and bearing against the edges of the ribs 195 and being disengaged from the magazine bar 288 so that it may freely move 100 downwardly when engaged by the picker.

105 During the normal operation of the machine a drop wire is always interposed between the rollers 219 and 232 and thus as above described the contacts 251 and 248 are kept in engagement. However, if for any reason there should be a failure of drop wires to separate the rolls, as for example by exhaustion of the drop wires in the magazine or by failure of the picker to deliver a drop wire, the approach of the rolls thus permitted 110 results as above described in a separation of the contacts 251 and 248 thus breaking the circuit through the driving motor and bringing the machine to rest.

115 In the present apparatus I have disclosed two separator fingers 116 and 116^a which operate alternatively but it is to be understood that one of such fingers may be omitted if desired although it is preferred to employ two such fingers since it increases the speed 120 of the machine. In the same way I have illustrated two bridge members 122 arranged at opposite sides of the guide down which the drop wires pass, but under some circumstances one of these bridge members with its 125 thread positioning mechanism may be omitted if desired, although for accuracy in operation I prefer to employ duplicate thread positioning mechanism.

130 While I have here shown thread separating

means of specific character it is to be understood that the invention broadly is not necessarily limited to this particular form of thread separating and positioning device but that other and equivalent means may be substituted therefor. It is also to be understood that the specific drive mechanism as herein disclosed, the specific arrangement and size of parts, the relative position, proportion and shape of parts is not a necessary part of the invention except as to its less important aspects nor is it essential that the carriage which supports the magazine or the magazine itself be of the specific character herein disclosed. While I have here shown a single magazine mounted upon a reciprocating carriage I contemplate that under some circumstances it may be desired to employ a plural magazine of the type disclosed in my prior Patent No. 1,516,675; dated November 25, 1924, and in such a case the carriage reciprocating means may be modified as may be desirable in order to secure the proper movement of the magazine to deliver the drop wires in the desired manner.

I claim:

1. A machine for associating detached loom elements with warp threads comprising means for presenting such an element for engagement with a thread and means for moving said presenting means in a path substantially parallel to the warp threads.

2. A machine for associating detached loom elements with warp threads comprising a guide for such elements, and means for moving said guide in a path substantially parallel to the warp threads.

3. A machine for associating detached loom elements with warp threads comprising a guide for such elements, and means for moving said guide both transversely and longitudinally of the warp threads.

4. A machine for engaging hair-pin drop wires with warp threads comprising means for positioning the wire in a plane transverse of the warp threads and for advancing the wire endwise to engage it with a thread, and means for moving said positioning means in a path substantially parallel to the warp threads.

5. A machine for engaging hair-pin drop wires with warp threads, comprising means for delivering a wire endwise toward the warp threads, a guide having a face with which the drop wire contacts as the wire advances toward warp-engaging position, said guide extending substantially from the delivery means to the plane of the warp threads and having an element projecting from said face and adapted to enter between the legs of the wire and thereby to prevent lateral movement of the latter relative to the guide.

6. An elongate compacted machine for associating detached loom elements with warp

threads comprising means for holding a series of such elements, the series extending substantially parallel to the direction of the warp threads, and means for delivering elements from said series in such manner as to form a plurality of banks upon the warp threads.

7. A machine for associating drop wires with warp threads comprising a magazine for holding a series of such drop wires, and means for moving the magazine both longitudinally and transversely of the warp threads.

8. A machine for associating detached loom elements with warp threads comprising a magazine carriage movable both longitudinally and transversely of the warp threads, means for moving the carriage intermittently longitudinally of the warp threads, the carriage comprising a magazine for holding a series of said elements, means for delivering said elements one by one from the series, and means responsive to failure of the delivering means to deliver elements from the series and by such response causing the machine to stop.

9. A machine for associating detached loom elements with warp threads comprising a magazine carriage movable both longitudinally and transversely of the warp threads, means for moving the carriage longitudinally of the warp threads, the carriage comprising a magazine for holding said elements in a series, means for discharging elements one by one from one end of the series, means for advancing the series bodily toward the discharging means, and means for guiding the discharged elements into position for engagement with corresponding warp threads.

10. A machine for associating detached loom elements with warp threads comprising a magazine for holding said elements in a series, means for discharging said elements one by one from one end of the series, and means engaging the other end of the series for advancing the series toward the discharging means, said advancing means comprising complementary friction clutch members, and pawl and ratchet means normally advancing one of said clutch members step-by-step.

11. A machine for associating detached loom elements with warp threads comprising a magazine for holding said elements in a series, means for discharging said elements one by one from one end of the series, said magazine comprising an elongate normally stationary bar for supporting said elements, and means for independently adjusting the height of each end of the bar whereby the bar may be adjusted bodily in a vertical direction with or without variation in the inclination of the bar.

12. A machine for applying hair-pin drop wires with warp threads having a magazine for holding said wires in series, means for

delivering said wires one by one from the magazine, a power driven element, a part tending to move into the path of said element, said part being held out of said path so long as the delivery means continues to deliver drop wires, said part when permitted to move into the path of said moving element being actuated by the latter to stop the machine.

13. In a machine for associating detached loom elements with warp threads having means for presenting such an element for engagement with a warp thread, said machine comprising clamping means disposed at opposite sides of said presenting means for clamping and positively holding a warp thread in position both vertically and horizontally for engagement by said element.

14. In a machine for associating drop wires with warp threads having means for separating a thread from a series of warp threads and for presenting a drop wire for engagement with the separated thread, said machine comprising thread manipulating instrumentalities and yielding means for actuating said instrumentalities.

15. In a machine for associating drop wires with warp threads having means for separating a thread from a series of warp threads and for presenting a drop wire for engagement with the separated thread, a thread retainer, a looper for moving the separated thread toward the retainer, and means for temporarily clamping the thread so as to prevent either horizontal or vertical movement thereby to ensure its engagement with the drop wire.

16. In a machine for associating drop wires with warp threads having means for separating a thread from a series of warp threads and for presenting a drop wire for engagement with the separated thread, a looper, a thread positioner, a thread clamp, a thread pusher, and a thread retainer, and means for moving the looper, positioner, clamp and pusher in timed relation.

17. A machine for associating detached loom elements with warp threads comprising means for presenting such an element for engagement with a thread, and means for moving said presenting means intermittently in a path substantially parallel to the warp threads.

18. A machine for associating detached loom elements with warp threads comprising means for presenting such an element for engagement with a thread, and means for moving said presenting means in a path substantially parallel to the warp threads during each interval between the presentation of successive elements.

19. A machine for associating drop wires with warp threads comprising means for presenting a drop wire in position for engagement with a thread, and means for moving said presenting means longitudinally of

the warp threads during each interval between the presentation of successive drop wires whereby to dispose the wires in a plurality of banks.

20. A machine for associating drop wires with warp threads comprising means for presenting a drop wire in position for engagement with a thread, means for progressing the presenting means transversely of the warp threads whereby to present wires for engagement with different threads, and means for moving the presenting means longitudinally of the warp threads during each interval between the presentation of successive drop wires whereby to dispose the wires in a plurality of banks.

21. A machine for associating detached loom elements with warp threads comprising a guide for such elements, means for moving said guide transversely of the warp threads, and means for moving said guide intermittently in a path substantially parallel to the warp threads.

22. A machine for associating detached loom elements with warp threads comprising a guide for such elements, and means for moving said guide intermittently and in opposite directions in a path substantially parallel to the warp threads.

23. A machine for associating detached loom elements with warp threads comprising a guide for such elements, and means including a cam for moving said guide intermittently, some at least of the movements of the guide being substantially parallel to the warp threads.

24. A machine for associating detached loom elements with warp threads comprising a guide for such elements, and means including a rotary cam having active portions and dwell portions for moving said guide intermittently, sometimes in one direction and sometimes in the opposite direction, longitudinally of the warp threads.

25. A machine for engaging hairpin drop wires with warp threads, comprising a guide member having a face which extends transversely of the warp threads, means for advancing a drop wire endwise along said face into engagement with a thread, and means for moving said guide in a path substantially parallel with the warp threads.

26. A machine for associating detached loom elements with warp threads comprising a magazine for holding a series of such elements, with the series extending longitudinally of the warp threads, and means for moving the magazine in a path substantially parallel to the warp threads.

27. A machine for associating detached loom elements with warp threads comprising a magazine carriage movable both longitudinally and transversely of the warp threads, means for supporting a series of such elements upon the carriage, means for discharging said

elements one by one from the series, and means for moving the carriage longitudinally of the warp threads in the interval between discharge of successive elements.

- 5 28. A machine for associating detached loom elements with warp threads comprising a magazine carriage movable both longitudinally and transversely of the warp threads, said carriage having a magazine for supporting a series of such elements, means for separating said elements one by one from the series and for guiding such separated elements into position for engagement with corresponding warp threads, and means for moving the 10 carriage intermittently both longitudinally and transversely of the warp threads.

29. A machine for associating detached loom elements with warp threads comprising a magazine carriage movable both longitudinally and transversely of the warp threads, and means for moving the carriage intermittently in a path substantially parallel to the warp threads, said carriage comprising a magazine for said elements, and means for 20 delivering said elements one by one from the magazine and for directing such separated elements into position for engagement with corresponding warp threads.

30. A machine for applying drop wires to warp threads comprising a frame movable transversely of the warp threads, means for moving the frame, a magazine carriage mounted upon the frame to move in a direction substantially parallel to the warp 35 threads, and means for intermittently moving said carriage.

31. A machine for applying drop wires to warp threads comprising a frame movable transversely of the warp threads, a magazine carriage mounted upon said frame to move in a direction substantially parallel to the warp threads, means mounted upon the carriage for delivering drop wires one by one for engagement with warp threads, means for 40 moving the carriage longitudinally of the warp threads whereby to deposit the drop wires in a plurality of banks, and means for moving the frame whereby to traverse said delivery means transversely across the warp 45 threads.

32. A machine for applying drop wires to warp threads comprising a frame movable transversely of the warp threads, a magazine carriage mounted upon said frame to move 55 in a direction substantially parallel to the warp threads, means mounted upon the carriage for delivering drop wires one by one for engagement with warp threads, means for moving the carriage longitudinally of the warp threads whereby to deposit the drop wires in a plurality of banks, intermittently operating means for moving the frame, and means responsive to absence of warp threads in position to receive drop wires for causing 60 said frame moving means to operate.

33. A machine for associating detached loom elements with warp threads comprising a magazine for holding said elements in a series, means for discharging said elements one by one from one end of the series, a follower member engaging the other end of the series for advancing the series bodily toward the discharging means, and drive means for moving the follower member, said drive means comprising a slip connection.

34. A machine for associating detached loom elements with warp threads comprising a magazine for holding said elements in a series, means for discharging said elements one by one from one end of the series, a follower member engaging the other end of the series, and means for advancing said follower member, said advancing means comprising a pawl and ratchet drive and a friction clutch.

35. A machine for applying hairpin drop wires with warp threads having a magazine for holding said wires in series, said magazine comprising an elongate normally fixed bar of substantially rectangular vertical section over which the wires are straddled, and means for independently adjusting the height of the opposite ends of the bar thereby permitting bodily vertical movement of the bar as well as variation in its inclination.

36. A machine for applying drop wires to warp threads comprising a frame movable transversely of the warp threads, a magazine carriage mounted upon said frame to move in a direction substantially parallel to the warp threads, means mounted upon the carriage for delivering drop wires one by one for engagement with warp threads, means for moving the carriage longitudinally of the warp threads whereby to deposit the drop wires in a plurality of banks, means for moving the frame, and a detector device normally engaging a warp thread or threads, said detector device moving when no longer engaged by a thread and thereby setting the frame moving means into operation.

37. A machine for associating detached loom elements with warp threads comprising a magazine carriage movable both longitudinally and transversely of the warp threads, means for moving the carriage longitudinally of the warp threads, the carriage comprising a magazine for holding said elements in a series, means for discharging said elements one by one from one end of the series, and means engaging the opposite end of the series for compacting said elements.

38. A machine for applying hairpin drop wires to warp threads, said machine having a magazine for holding said wires in series, means for discharging elements in succession from the magazine, motive means for driving the machine, an electrical circuit controlling the operation of said motive means, an element driven by said motive means, and means for breaking the circuit comprising a

part tending to move into the path of said driven element and to be actuated thereby to break the circuit, and means preventing said part from engaging said driven element so long as wires are delivered in orderly succession from the magazine.

39. A machine for applying hairpin drop wires to warp threads, said machine having a magazine for holding said wires in series, means for discharging elements in succession from the magazine, motive means for driving the machine, an electrical circuit controlling the operation of said motive means, an element driven by said motive means, a circuit breaker comprising normally engaging contacts, one of said contacts having an actuating part, an element driven by said motive means, and means operative, upon failure of the wire discharging means to deliver wires in orderly succession, for causing said contact actuating part and the driven element to engage, thereby separating said contacts.

40. In a machine for associating detached loom elements with warp threads having means for presenting such an element for engagement with a warp thread, said presenting means including an elongate guideway for said elements, and relatively movable thread clamping means having spaced thread holding members at opposite sides of the guideway, said members being disposed in the plane of said guideway at the instant of presentation of one of said elements whereby accurately and positively to hold the thread, both horizontally and vertically in position for engagement by said element.

41. In a machine for associating drop wires with warp threads having means for separating a thread from a series of warp threads and for presenting a drop wire for engagement with the separated thread, said machine comprising a pivoted thread positioner, a pivoted clamp for holding the separated thread in contact with the positioner, and common means for moving the positioner and clamp in opposite directions.

42. In a machine for associating drop wires with warp threads having means for separating a thread from a series of warp threads and for presenting a drop wire for engagement with the separated thread, said machine comprising a clamping lever, a thread positioning lever, and an actuating member, a pair of links pivotally connected to said actuating member, one link being connected to the clamping lever and the other link being connected to the positioning lever.

43. In a machine for associating drop wires with warp threads having means for separating a thread from a series of warp threads and for presenting a drop wire for engagement with the separated thread, said machine comprising a pusher lever, a thread clamping lever, a rocking actuator, and links

for transmitting movement from the actuator to the pusher and clamping lever.

44. In a machine for associating drop wires with warp threads having means for separating a thread from a series of warp threads and for presenting a drop wire for engagement with the separated thread, said machine comprising a thread positioner, a rock shaft, and means for transmitting movement from the rock shaft to the positioner.

45. In a machine for associating drop wires with warp threads having means for separating a thread from a series of warp threads and for presenting a drop wire for engagement with the separated thread, said machine comprising oppositely moving members for clamping and holding the separated thread in predetermined position, a rock shaft, and link and lever means for transmitting movement from the rock shaft to said clamping and holding members.

46. In a machine for associating drop wires with warp threads having means for separating a thread from a series of warp threads and for presenting a drop wire for engagement with the separated thread, said machine comprising thread manipulating instrumentalities, a rock shaft, and means including resiliently yieldable connections for transmitting movement from the rock shaft to said instrumentalities.

47. In a machine for associating detached loom elements with warp threads having means for presenting such an element for engagement with a warp thread, said machine comprising means for separating a thread from a series of warp threads, a rock shaft, means for rocking the shaft, and means for clamping the separated thread in position for engaging said element, said clamping means comprising relatively movable parts one at least of which is actuated by the rock shaft.

48. In a machine for associating detached loom elements with warp threads having means for presenting such an element for engagement with a warp thread, said machine comprising means for separating a thread from a series of warp threads, clamping means comprising relatively movable parts for holding the separated thread in position for engaging said element, and yielding means for imparting motion to said thread holding means.

49. In a machine for associating detached loom elements with warp threads having means for presenting such an element for engagement with a warp thread, and means for separating a thread from a series of warp threads, said machine comprising guide means having a surface along which the separated thread is moved, means for moving the separated thread along said surface and for positively holding it against movement either vertically or horizontally in a position for engaging said element, and yielding

means for actuating said thread moving and holding means.

50. In a machine for associating detached loom elements with warp threads having 5 means for presenting such an element for engagement with a warp thread, said machine comprising means for separating a thread from a series of warp threads, a thread positioner, thread clamping means for holding 10 the separated thread against the positioner, and means for actuating the clamping means.

51. In a machine for associating detached loom elements with warp threads having means for presenting such an element for engagement with a warp thread, said machine comprising means for separating a thread from a series of warp threads, guide means having a surface along which the separated thread is moved, said guide means being provided 15 with a fixed retainer, and means for moving the separated thread along said guide surface until it engages the retainer.

52. In a machine for associating detached loom elements with warp threads having 25 means for presenting such an element for engagement with a warp thread, said machine comprising means for separating a thread from a series of warp threads, a fixed retainer, means for moving the separated thread to a 30 position for engagement with said element, for causing the thread to dwell in said position until engaged by said element, and for thereafter moving the thread toward the retainer.

53. In a machine for associating drop wires with warp threads having means for separating a thread from a series of warp threads and for presenting a drop wire for engagement with the separated thread, a looper for 40 moving the separated thread, and means for temporarily detaining the thread moved by the looper and for clamping it to prevent either vertical or horizontal movement in a position for engagement by the drop wire.

54. In a machine for associating drop wires with warp threads having means for separating a thread from a series of warp threads and for presenting a drop wire for engagement with the separated thread, a looper lever for 50 moving the separated thread, means for moving the looper lever, means movable into the path of the thread moved by the looper for gripping the thread and detaining it in position to engage a drop wire, and means for moving said detaining means.

55. In a machine for associating drop wires with warp threads having means for separating a thread from a series of warp threads and for presenting a drop wire for engagement with the separated thread, means for moving the separated thread, means for detaining the thread so moved in position for engagement with a drop wire, means for 60 clamping the detained thread, and means for 65

continuing the movement of the detained thread after engagement with a drop wire.

56. In a machine for associating drop wires with warp threads having means for separating a thread from a series of warp threads 70 and for presenting a drop wire for engagement with the separated thread, a pair of spaced supports disposed respectively at opposite sides of the wire presenting means, thread manipulating instrumentalities upon 75 each support, a rock shaft and means for transmitting movement from the rock shaft to both sets of instrumentalities.

57. In a machine for associating drop wires with warp threads having means for separating a thread from a series of warp threads 80 and for presenting a drop wire for engagement with the separated thread, a pair of spaced bridge pieces disposed respectively at opposite sides of the wire presenting means, link and lever mechanism constituting thread manipulating means mounted on each bridge piece, a rock shaft, and yielding means for transmitting movement from the rock shaft to each of said mechanisms. 85

58. In a machine for associating drop wires with warp threads having means for separating a thread from a series of warp threads and for presenting a drop wire for engagement with the separated thread, a plurality 90 of thread manipulating levers, a common pivot for two of said levers, means for moving said latter levers in timed relation, and a link connecting one of said latter levers to a third lever. 95

CERTIFICATE OF CORRECTION.

Patent No. 1,811,675.

Granted June 23, 1931, to

SEBASTIANO MAGNANO.

It is hereby certified that error appears in the printed specification of the above numbered patent requiring correction as follows: Page 12, line 64, claim 6, strike out the words "An elongated compacted" and insert the article A; same page and claim, line 66, strike out the article "a" and insert an elongated compacted; and that the said Letters Patent should be read with these corrections therein that the same may conform to the record of the case in the Patent Office.

Signed and sealed this 11th day of August, A. D. 1931.
